UNITED STATES PATENT OFFICE.

LEO M. ANDERSON, OF NEW YORK, N. Y.

GAZING-BOWL.

Specification of Letters Patent. Patented Aug. 23, 1921.

1,388,789.

Application filed October 22, 1920. Serial No. 418,676.

To all whom it may concern:

Be it known that I, LEO M. ANDERSON, a citizen of the United States, and a resident of the city of New York, borough of Manhattan, county and State of New York, have invented a new and Improved Gazing-Bowl, of which the following is a full, clear, and exact description.

This invention relates to a gazing bowl, and has for an object to provide a receptacle of this character which is artistic and ornamental, and provides at the same time a medium upon which persons may at will focus their gaze whereby the concentration of 15 their thoughts may be assisted.

Another object resides in the provision of means whereby this desired concentration may be further assisted by the preparation of the inner face of the receptacle at which 20 the person is gazing.

A still further object resides in the particular construction and arrangement of parts hereinafter set forth and claimed, and shown in the accompanying drawings.

In general, my invention comprises a receptacle which is treated on its interior surface in such manner as to produce a highly polished surface which may be colored to produce a certain desirable effect. This receptacle may be filled with some liquid preferably transparent, which forms a reflecting surface into which the person using the device may gaze, for the purpose of assisting him in concentrating his thoughts. Other 30 features of the invention will be apparent from the description of the claims herein-after set forth, when considered in connection with the drawings.

The invention is illustrated in the drawings of which—

Figure 1 is a central vertical section through the device; and

Fig. 2 is a plan view of the device.

As shown in the drawings, the invention 45 comprises a receptacle which has a broad, flat, base portion 1 and shallow gracefully curved side portions 2. This receptacle may

be made of any suitable material, but preferably is made of copper or brass, or other artistic material. The inner surface 3 of 50 this metal is treated with any desired or suitable acid to color the inner surface in whatever manner is desirable.

Into and against the inner face 3 of this receptacle thereafter a lining 4 of glass or 55 other transparent medium is blown or placed by any suitable operation known in the art.

Into the vessel is then introduced a body of liquid, preferably water 5, and this in 60 combination with the highly polished interior surface of the bowl, forms a reflecting and transparent surface which simulates the highly reflective surfaces of solid crystal hitherto used, and enables the operator to 65 focus his gaze on some pleasing artistic object for the purpose above mentioned. The fact that the interior surface of the metal receptacle is highly polished and sometimes colored, further enhances the mental effect 70 of this reflection on the operator.

Other materials may be used in the formation of this device than those mentioned, and modification in the form may also be affected without departing from the spirit 75 of the invention as set forth.

What I claim is:

1. A gazing bowl comprising an open-topped metallic receptacle having curved 80 sides suitably treated to produce any desired color effect thereon, and a lining of transparent material placed against the inner surface of this receptacle to form a highly polished reflective surface, said receptacle adapted to receive a body of transparent liquid.

2. A gazing bowl comprising a broad shallow open-topped metallic receptacle having curved side portions and a lining on the 90 inner face thereof of some transparent material, and adapted to receive a body of transparent liquid.

LEO M. ANDERSON.
